UNITED STATES PATENT OFFICE.

LOUIS BERG, OF CHICAGO, ILLINOIS, ASSIGNOR TO STEWART-WARNER SPEEDOMETER CORPORATION, OF CHICAGO, ILLINOIS, A CORPORATION OF VIRGINIA.

VACUUM FUEL-FEED DEVICE.

1,277,685.

Specification of Letters Patent.

Patented Sept. 3, 1918.

Application filed September 10, 1917. Serial No. 190,679.

To all whom it may concern:

Be it known that I, Louis BERG, a citizen of the United States, residing at Chicago, in the county of Cook and State of Illinois, have invented new and useful Improvements in Vacuum Fuel-Feed Devices, of which the following is a specification, reference being had to the accompanying drawings, forming a part thereof.

10 The purpose of this invention is to provide an improved construction in a vacuum fuel feeding device for internal combustion engines, the specific purpose being to afford a simpler means than has heretofore been 15 used for alternating the domination of the suction and atmospheric pressure in the vacuum chamber of such a device. It consists in the elements and features of construction, shown and described, as indicated 20 in the claims.

In the drawings, which show a modification of the invention disclosed and claimed broadly in my co-pending application No. 190,678, filed September 10, 1917:

25 Figure 1 is a diagrammatic view presenting the main elements of the invention in their general relation as assembled on an automobile.

Fig. 2 is a vertical axial section of the 30 vacuum feed device proper, showing the several elements in the vacuum chamber at the position occupied during filling,—that is, during the domination of the suction.

Fig. 3 is a view similar to Fig. 2, showing the position of the parts during emptying of the vacuum chamber,—that is, during the domination of the atmospheric pressure.

In the drawings 1 represents the main 40 low level liquid fuel supply tank. 2 is the vacuum chamber; 3 is the liquid conduit for supplying the vacuum chamber from the low level tank; 4 is the reservoir or reserve chamber which is supplied with the 45 liquid fuel from the vacuum chamber, the structure being in the familiar form in which the vacuum chamber is suspended within the reservoir, 4, with an annular space, 5, at the upper part of said reservoir 50 around the vacuum chamber. 6 is the discharge pipe from the vacuum chamber into the reservoir, 4; 7 is the valve which controls the liquid discharge. 8, is the suction connection to the vacuum chamber, 9^a, 55 the atmosphere inlet port which is formed

in a fitting at the bottom of the vacuum chamber which is connected by a pipe, 9, extending in the reservoir, 4, up to near the top of the annular portion thereof. 10 is a frame or hanger which is rigidly supported 60 in the vacuum chamber conveniently by being suspended from the top plate, 2^a, thereof, affording guidance in its top and bottom bars for the stem, 11^a, of the atmosphere inlet valve, 11. Within said frame, 10, mounted and guided on the valve stem, 11^a, there is an upper buoy, 12, having very slight range of movement on the sliding stem, being stopped at its lower side by a pin, 11^b, and at its upper side by a pin, 11^c, set 70 through said stem, a very light spring, 13, being interposed between the buoy at the upper side and the pin, 11^c, tending to hold the buoy normally stopped against the lower pin. 14 is a smaller float mounted in the 75 lower part of the chamber, also freely sliding on valve stem, 11^a, and stopped at its lower side by a pin, 11^d, set through the stem, whereby the weight of said lower buoy tends to operate for seating the atmosphere 80 valve, 11, when said lower buoy is at its lowest position. Fulcrumed on the frame, 10, there is a latch, 16, and preferably two such latches are employed, as illustrated, at 85 diametrically-opposite positions with respect to the valve stem, 11^a. At their upper ends these latches are adapted to engage under the abrupt lower shoulder, 15^b, of a hub, 15, with which the upper buoy, 12, terminates at its lower side, the latches being adapted to swing about their fulcrums clear of said shoulder to permit the ends of the latches to pass up along the side of the hub, as shown in Fig. 2. At the lower end below the fulcrum each latch has an 95 abutment, 16^a, which engages the slots, 18^a, in cams, 18^b, carried by the lower buoy, 14, the two cams for the two latches shown being formed as up-bent portions of a plate, 18, which is mounted upon the upper side 100 of said lower buoy.

The operation of the device described may be well understood from the structure itself, but may be further explained.

The various chambers, excepting the main 105 low level supply tank, being empty, the suction connection pipe, 8, being connected with the intake manifold of the engine, during the operation of the engine, partial vacuum is produced in the vacuum chamber, causing 110

liquid to be forced by atmospheric pressure from the main low level tank up into said vacuum chamber. At the initial stage of emptiness of the vacuum chamber, it will be understood that the atmosphere inlet valve, 11, is seated and is held on its seat by the weight of both the buoys. As the liquid rises in the vacuum chamber, the lower buoy being first submerged, tends to rise, but is prevented from doing so by the engagement of the lower arms of the latches, 16, in the cams, 18^b, and the engagement of the upper ends of the latches against the side of the hub, 15, of the upper buoy. As the liquid continues to rise, eventually the upper buoy becomes submerged and buoyed to a sufficient extent to cause it to rise, compressing the light spring, 13, at the top and carrying the lower abrupt shoulder, 15^b, of the hub, 15, up past the upper end of the latches; whereupon the upward buoyed action of the lower buoy, which is completely submerged, operating by means of the cams, 18^b, upon the lower arms of the latches forces their upper ends inward under the abrupt shoulder 15^b, and the lower buoy being thereby released and rising, releases the atmosphere valve which is immediately pulled off its seat, first, by the reaction of the spring, 13, and then by the further uplifting action of the upper buoy. The atmosphere being admitted and dominating over the suction, the liquid in the vacuum chamber falls by gravity out past the valve, 7, into the reservoir, 4. The upper buoy soon ceases to be upheld by the liquid, but is prevented from falling and causing the atmosphere valve to be closed because it is held in upper position by the engagement of the latches, 16, under said abrupt shoulder, 15^b, of the hub, 15, of said upper float; and this condition continues until the liquid has fallen so far that the lower buoy, 14, ceasing to be upheld by the liquid, will fall, and by the action of the cams, 18^b, on the lower ends of the latches, withdraws the upper ends of the latches from under said shoulder, permitting said upper buoy to fall and to carry the atmosphere inlet valve down with it. Thus said atmosphere inlet valve becomes closed when the liquid level of the chamber has fallen so as to leave the lower buoy only partly submerged; the low liquid level of the vacuum chamber being thus very nearly the

bottom of the chamber, the atmosphere pressure being cut off, the suction again dominates, and the chamber becomes refilled as in the first instance.

I claim:

1. In a liquid fuel feeding apparatus in combination with a main supply tank at a low level; a vacuum chamber at a higher level, a conduit for conducting liquid fuel from the said tank to the vacuum chamber, the vacuum chamber having a liquid discharge port and a valve controlling the same, adapted to be opened by gravity flow, and to be held on its seat by the suction in the vacuum chamber, said chamber having a suction connection and an atmosphere inlet port; a valve controlling the atmosphere inlet port; two buoys in the chamber at different heights, the upper buoy being operatively connected with the atmosphere valve for opening it when said upper buoy rises, and for closing it when the upper buoy falls, and means by which the lower buoy locks the upper buoy in elevated position when the lower buoy falls.
2. In a construction such as set out in claim 1, said locking means consisting of a latch having a fixed fulcrum and adapted to engage the upper buoy at the highest position thereof; means by which the lower buoy actuates said latch.
3. In a construction such as set out in claim 2, foregoing, the means for actuating the latch being a cam carried by the lower buoy.
4. In a construction such as set out in claim 1, both of the buoys mentioned being guided on the stem of the atmosphere inlet valve, the upper buoy having a slight range of movement thereon, and a spring reacting between the valve stem and said upper buoy tending to hold the buoy at the lower limit of its said slight range.
5. In a construction such as set out in claim 2, a hanger rigidly mounted in the vacuum chamber, the atmosphere inlet valve having its stem guided for opening and closing movement in said hanger, and the latch being fulcrumed on the hanger.

In testimony whereof I have hereunto set my hand at Chicago, Illinois, this 30th day of August, 1917.

LOUIS BERG.
